SCOREBOARD

Mark Rubinoff, New York, N. Y.

Application May 26, 1950, Serial No. 10,213

Term of patent 7 years

(Cl. D34—5)

To all whom it may concern:

Be it known that I, Mark Rubinoff, a citizen of the United States and a resident of the city of New York, State of New York, have invented a new, original, and ornamental Design for Scoreboard, of which the following is a specification, reference being had to the accompanying drawing, forming part thereof.

Fig. 1 is a top plan view of a score board, showing my new design; and

Fig. 2 is a sectional view thereof taken on line 2—2 of Fig. 1.

I claim:

The ornamental design for a scoreboard, as shown.

MARK RUBINOFF.
